UNITED STATES PATENT OFFICE.

GEORGE N. TAYLOR, OF EAST PROVIDENCE, RHODE ISLAND, ASSIGNOR TO UNIVERSAL WINDING COMPANY, OF BOSTON, MASSACHUSETTS, A CORPORATION OF MASSACHUSETTS.

TENSION DEVICE AND YARN CLEANER.

1,424,124.

Specification of Letters Patent. Patented July 25, 1922.

Application filed May 23, 1921. Serial No. 471,765.

To all whom it may concern:

Be it known that I, GEORGE N. TAYLOR, of East Providence, in the county of Providence, State of Rhode Island, a citizen of the United States, have invented certain new and useful Improvements in Tension Devices and Yarn Cleaners, of which the following is a specification.

My invention is an improved tension-device and yarn-cleaner for use with winding machines and other textile apparatus.

One object of the invention is to provide an improved device of the type specified adapted to apply a uniform tension on the thread or yarn passing therethrough, while also having a more sensitive yielding-action to allow the passage of knots, enlargements or irregularities in the yarn without subjecting the latter to undue resistance or strain.

Another object of the invention is to provide means for cleaning or clearing the yarn as it passes through the device to remove specks, motes or slubs therefrom.

Another object of the invention is to provide a tension-device and yarn-cleaner of simplified construction which is economical to manufacture, convenient to operate and proof against derangement or getting out of order.

The manner and means for carrying out these improvements are fully set forth in the following specification which describes a preferred embodiment of the invention as illustrated by the accompanying drawings.

In the drawings:

Fig. 1 is a plan view of my improved tension-device and yarn-cleaner;

Fig. 2, a side elevation of the same looking in the direction indicated by the arrow 40 2 in Fig. 1;

Fig. 3, a vertical sectional view of the device taken on the line 3—3 of Fig. 1; and

Fig. 4, a side elevation of the yarn-cleaning blade or scraper illustrating its relation 45 to the bottom-plate or base of the device which is shown in cross-section on the line 4—4 of Fig. 1.

Referring to the several views of the drawings, my improved device is preferably 50 constructed with its parts stamped out and struck up from sheet-metal to adapt it for economical manufacture. The main support for the device consists of a horizontal base-plate 5 having its rearward end bent 55 down at right-angles to its main plane to

provide a vertical flange 6. The base-plate 5 is adapted to set down against the top of a rectangular rod or bar 7 with its flange 6 abutting the rearward side thereof, and beneath the plate is an angle-shaped bracket 60 or clamp 8 which fits around the opposite sides of the rod 7 and is secured to the plate 5 and its flange 6 by means of suitable screws 9 and 10. The supporting-rod 7 extends horizontally across the front of the 65 machine on which the device is used and may be held in suitable standards or brackets mounted on the frame of the machine, but not herein illustrated. As shown in Fig. 1, the plate 5 is shaped with a circular 70 contour on its forward edge and is extended at one side to form a finger or horn 11. The rearward side of the finger 11 has a straight edge leading into an offset, curved slot or crook 12 which provides a guiding passage 75 or entrance for the yarn to direct it into place between the tension-disks to be later described. From the slot or guideway 12 the side of the plate 5 extends rearwardly at a slight angle whereby when the yarn is 80 drawn across its edge it will have a tendency to slide forward into the guideway.

At the approximate center of the forward, overhanging portion of the plate 5 is a vertical pin or spindle 14 which may be secured 85 to the plate by riveting it through a hole therein, as shown in Fig. 3, or through any other suitable method of fastening it in place thereon. The spindle 14 forms the pivot for a pair of tension-disks 15 and 16 90 which serve as the means for applying the tension on the yarn drawing between them. As illustrated in Fig. 3, the disks 15 and 16 are struck up from relatively thin sheet-metal and shaped to a generally concavo-convex form in cross-section, with axial holes 17 for receiving the spindle 14, and oppositely-flaring rims 18 at their peripheries. The oppositely-flaring rims 18 form a V-shaped entrance for the yarn to direct 95 it into place between the disks, and the adjacent outer positions of the disks bear against the yarn to apply the resistance or drag which causes the tensioning action. The tension disks 15, 16 are pressed together 100 to cause them to bear against the yarn with a yielding pressure by means of a combination of spring and weights arranged as next described. The lower disk 16 is mounted on the spindle 14 with its rim 18 set into a cir- 110

cular counterbore 19 on the top of the plate 5, the edge of the rim being thus recessed beneath the face of the plate so that the yarn will ride up across it without obstruction in entering it between the disks. The upper disk 15 is mounted on the spindle 14 in a similar manner and sets down against the lower disk in opposite relation thereto. Surrounding the spindle 14 above the disk 15 is a relatively fine, helical spring 20 arranged with its lower end bearing against the disk. Above the spring 20 is a sleeve 21 surrounding the spindle 14 and adapted to slide freely thereon. The sleeve 21 is formed 10 with an enlargement at its lower end providing a tubular skirt 22 surrounding the spring 20 to serve as an enclosing shield or guard therefor. The enlargement 22 also provides a shoulder 23 at its upper end which serves 15 as a ledge or abutment for supporting one or more disk-shaped washers or weights 25 set down over the sleeve 21.

Secured to the upper face of the plate 5 is a relatively flat guard-ring 27 which encircles the peripheries of the disks 15 and 16 to serve as a means for directing the yarn into place therebetween. The guard-ring 27 is formed at one side with a portion of its circumference depressed slightly below 20 the plane of its main portion to adapt it to set down against the top of the plate 5 whereby it may be secured fixedly in place thereon by means of suitable rivets or screws 28. At the opposite side of the ring 27 is 25 an ear 29 bent upwardly in vertical position to adapt it to serve as a support for an elbow-shaped arm 30. The arm 30 carries a stud or rivet 31 by means of which it is pivoted to the ear 29 to adapt it to swing 30 thereon. The horizontal portion of the arm 30 reaches inwardly across the top of the bearing-spindle 14 and is provided with a 35 perforation 32 at its end adapted to snap over the upper rounded end of the spindle. Through this arrangement the arm 30 acts 40 as a retainer for the weight-holding sleeve 21 to prevent it from being lifted off from the spindle 14. The arm 30 may be released from the end of the spindle 14 and swung 45 to one side thereof to allow for placing the weights 25 on the sleeve or holder 21; and when it is snapped back into place again, as shown in Figs. 2 and 3, it serves as a guard 50 to prevent accidental removal of the weights.

At the rearward side of the plate 5 is an upstanding ear 34, see Figs. 1, 2 and 4, on which the yarn-cleaner or scraper-blade 35 is mounted. The blade 35 consists of a 60 flat strip of sheet-metal supported on the vertical ear 34 with its lower edge set slightly raised above the top of the plate 5. At its outer or left-hand end the blade 35 overhangs the side of the plate 5, see 65 Fig. 4, and is provided with an inwardly in-

clined side 36 adapted to guide the yarn down in under its lower edge so that it will draw through the slot 37 between the blade and the plate 5. The blade 35 is supported on the ear 34 by means adapting it to be 70 adjusted up and down thereon to vary the width of the slot 37 beneath it, and to also adapt it to be set with its lower edge in exact parallelism with the upper face of the plate 5. As shown in Fig. 4, the blade 35 is attached to a slide 40 formed from sheet-metal and provided with flanges 41 bent back to overlap the sides of the ear 34. The blade 35 is fastened to the slide 40 by means of screws 42 inserted through enlarged holes 43 in the blade and screwed into the slide. The enlarged holes 43 allow the blade 35 to be tilted on the slide 40 when the screws 42 are loosened whereby to adjust its lower edge in parallelism with the 80 top of the plate 5; while a larger screw 44 extends through a slot 45 in the blade and slide and screws into the ear 34 to serve as a means for clamping the blade in fixed position after its adjustment. The method 85 of operation of the complete device is as follows:

The device is attached to the rod 7 in position for the yarn or thread to deliver therefrom to the winding machine or other apparatus, not herein illustrated, and usually the yarn draws off from a source of supply, such as a cap or bobbin, placed below the tension-device. In threading the device the yarn *y*, represented by dot-and-dash lines, is drawn up from the supply-bobbin and laid across the plate 5 in back of the finger 11 so that it will draw into the guideway 12. The yarn is next drawn forward and passed around in under the guard-ring 27 and then back in under the cleaner-blade 35, whence it is led to the winding-spindle or other element of the machine by which it is to be taken up. As the yarn is drawn taut it will be acted upon by the guideway 12 and the guard-ring 27 to direct it into place between the tension-disks 15 and 16 so that it will lead across the faces of the disks and around the spindle 14 with a slight bend as illustrated in Fig. 1. The cleaner-blade 35 is next adjusted to provide that the slot 37 beneath its lower edge is of proper width to allow the yarn to pass freely therethrough, while at the same time adapting the edge of the 110 blade to bear against the yarn to scrape off any motes, specks or foreign substances adhering thereto. The required number of tension-weights 25 are placed on the weight-holder or sleeve 21 to apply the amount of 115 tension required and the device is then ready for operation.

As the yarn *y* is taken up by the winding machine or other apparatus it will feed between the tension-disks 15 and 16 with the 120 125 130

latter applying a slight resistance to its draft. As the yarn draws through the disks 15 and 16 toward their central axis in one direction and away from the axis in another direction it will have a tendency to set up a rotative action of the disks about the spindle 14 whereby to constantly alter the point of contact of the yarn at the peripheries of the disks to prevent wearing 10 grooves therein.

A particular feature of improvement in the present device is the arrangement for taking the load of the tension-weights 25 on the spring 20 which is interposed between 15 the weight-holder 21 and the upper disk 15. The purpose of this arrangement is to provide for a more resilient action and a quicker relief of the pressure of the disks on the yarn when a knot or enlargement passes 20 through the device. Heretofore it has been the usual practice to arrange the tension-disks with the pressure weights acting directly against them, and it is obvious that in order to separate or force the disks apart to 25 allow the passage of a knot or enlargement therebetween it is necessary to raise or lift the weights bodily with the upper disk. The weights are naturally subject to the effect of considerable inertia and hence do not 30 respond quickly and sensitively to the action of the yarn when it is required to force the disks apart; consequently in devices of this type having the weights bearing directly against the disks the resistance to the separation 35 of the disks is so great as to strain and sometimes break a fine thread or filament. In my present improved arrangement the tendency of a knot or enlargement in the yarn to open the disks is resisted only by 40 the relatively light spring 20, and hence the disks will yield quickly and sensitively without imposing undue strain on the yarn. Stated briefly, the present improvement provides for a more sensitive and quickly-responsive yielding action or relief of pressure 45 of the disks on the running yarn, to allow the passage of knots and enlargements therethrough, and hence the danger of strain or breakage of the yarn is practically eliminated. Furthermore, since the weights are 50 not raised and lowered at each rise and fall of the upper disk there is less tendency to set up a chattering or vibrating action of the weights and therefore the pressure of the disks on the yarn does not fluctuate so that 55 the tension applied thereto remains more constant and uniform.

In addition to these advantages as above pointed out my improved device is also designed for ease and convenience of operation, particularly as regards the automatic threading of the yarn thereinto, and the means for retaining it in predetermined position to secure the proper operative effect 60 thereon. It is also to be observed that the

improved yarn-cleaner or scraper-device provides for more convenient and accurate adjustment of the scraping-element to increase the efficiency of the apparatus for the purpose intended.

While I have herein illustrated and described a preferred embodiment of the device it is to be understood that modifications may be made in its structure and arrangement without departing from the spirit or scope of the invention; therefore, without limiting myself precisely to the present disclosure, I claim:

1. In a tension-device, the combination of a tension-element adapted to bear against a running yarn to cause resistance to its draft, gravity-operated means for applying pressure on the tension-element to cause it to act on the yarn, and resilient means interposed between the gravity-means and the tension-element to adapt the latter to yield without overcoming the inertia of the gravity-means.

2. In a tension-device, the combination of a tension-element adapted to bear against a running yarn to apply tension thereto, a weight for applying pressure to the tension-element to cause it to act on the yarn, and resilient means interposed between the weight and the tension-element to allow the latter to yield freely without moving the weight when a knot or enlargement passes through the tension-device.

3. In a tension-device, the combination of a pair of tension-elements adapted to bear against a running yarn passing therebetween, gravity-operated means for applying pressure to the tension-elements to cause them to act on the yarn, and resilient means interposed between the gravity-means and the tension-elements to allow a yielding action of the latter without overcoming the inertia of the gravity-means.

4. In a tension-device, the combination with a pair of tension-elements, of a weight for applying pressure to the tension-elements to cause them to bear against the yarn to apply tension thereto, and a spring interposed between the weight and the tension-elements, said spring adapted to yield to allow separation of the tension-elements without moving the weight.

5. A tension-device comprising a pair of rotatable disks adapted to bear against a yarn drawing therebetween, a weight for applying pressure to the disks to cause them to act on the yarn to apply resistance to its draft, and a spring interposed between the weight and the tension-elements to adapt the latter to yield to allow the passage therethrough of knots or irregularities in the yarn without moving the weight.

6. A tension-device comprising a spindle, a pair of disks rotatable on the spindle and arranged to bear against the yarn running between them, weights slidable on the spin-

dle to apply pressure on the disks, and a spring interposed between the weights and the disks to provide for a sensitive yielding action of the latter without raising the 5 weights.

7. A tension-device comprising tension-elements adapted to bear against a running yarn to apply resistance to its draft, a weight-holder adapted to apply pressure to the 10 disks to cause them to act on the yarn, weights on said holder, and resilient means interposed between the weight-holder and the tension-elements to adapt the latter to yield without moving the weights.

8. A tension-device comprising a spindle, tension-disks mounted in opposed relation on the spindle to adapt them to bear against a yarn drawing therebetween, a weight-holder 15 slideable on the spindle, weights on said holder, and a spring interposed between the weight-holder and the disks to allow the latter to yield without moving the weights.

9. A tension-device comprising a spindle, disks mounted in superimposed relation on 20 said spindle to adapt them to bear against a yarn drawing therebetween, a sleeve slideable on the spindle, weights adapted to be mounted on the sleeve, and a spring surrounding the spindle between the sleeve and 25 the disks to transmit the pressure of the weights to the disks.

10. A tension-device comprising a spindle, a pair of tension-disks mounted on said spindle to adapt them to bear against a yarn 30 drawing therebetween, a spring surrounding the spindle above the upper disk, a sleeve slideable on the spindle and provided with a shouldered enlargement at its lower end arranged to enclose the spring, and weights 35 held on the sleeve abutting its enlarged shouldered portion.

11. In a tension-device, the combination 40 of a base-plate formed with a circular recess on its upper face, a spindle projecting upwardly from said plate, a pair of tension-disks mounted on said spindle, said disks having flaring flanges at their peripheries with the edge of the flange of the lowermost disk resting within the recess of the base-plate, and weights slideable on the spindle 45 to apply pressure to the upper disk to adapt it to bear against the yarn drawing between the disks.

12. In a tension-device, the combination with a support, of a spindle projecting upwardly from the support, a pair of tension-disks mounted on said spindle and formed with outwardly flaring rims at their peripheries, means for applying pressure on the 55 disks to cause them to act on the yarn drawing between them, and a guard-ring mounted on the support and surrounding the peripheries of the disks in close proximity thereto whereby to act to direct the yarn into position between the disks. 60

13. In a tension-device, the combination with a support, of a spindle projecting from 65 said support, a pair of tension-disks mounted on the spindle, means slideable on the spindle to adapt it to apply pressure to the disks 70 to cause the latter to bear against the yarn passing between the disks, and an elbow-shaped arm hinged to the support and adapted to engage the end of the spindle to retain the pressure-means in place on the 75 spindle.

14. In a tension-device, the combination with a base-plate provided with a finger 80 projecting from the side thereof and a curved guideway cut into the side of the plate at the rear of the finger, a spindle projecting upwardly from the plate, tension-disks mounted on said spindle and provided with oppositely flaring rims at their peripheries, and a guard-ring surrounding the rims 85 of the disks in raised position above the plate to direct the yarn leading through the guideway to cause it to enter between the flaring rims of the disks.

15. In a tension-device, the combination 90 with a base-plate having an upstanding ear at one side, of a spindle projecting upwardly from the plate, tension-disks mounted on said spindle to adapt them to bear against the yarn drawing therebetween, a slide 95 slideable on the ear of the plate, a yarn-cleaning blade adjustable on said slide to adapt its edge to be set in parallel relation with the top of the plate, and means to clamp the slide against the ear with the blade adjusted 100 in spaced relation to the plate to provide a slot for the yarn drawing from the tension-disks.

In testimony whereof I affix my signature.

GEORGE N. TAYLOR.
